US00D996814S

(12) **United States Design Patent** (10) **Patent No.:** **US D996,814 S**
(45) **Date of Patent:** **** Aug. 29, 2023**

(54) **PROTECTIVE COVER SKIN FOR
ELECTRONIC DEVICE**

- (71) Applicant: **elago CO. LTD**, Goyang-si (KR)
(72) Inventors: **Chanwoo Lee**, Goyang-si (KR); **Chong Min Kim**, Seoul (KR)
(73) Assignee: **elago CO. LTD**, Goyang-si (KR)
(**) Term: **15 Years**

(21) Appl. No.: **29/719,114**

(22) Filed: **Dec. 31, 2019**

(51) **LOC (14) Cl.** **03-01**
(52) **U.S. Cl.**

(57) **CLAIM**

The ornamental design for a protective cover skin for electronic device, as shown and described.

DESCRIPTION

FIG. 1 is a front, top, and right perspective view of a protective cover skin for electronic device, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a rear, top, and left perspective view thereof. The broken lines shown in FIGS. 3 and 7 depict parts of the protective cover skin for electronic device that form no part of the claimed design.

1 Claim, 6 Drawing Sheets
